UNITED STATES PATENT OFFICE

2,594,340

CENTRIFUGALLY ARMED FUSE

George M. O'Rear, United States Navy

Application September 19, 1940, Serial No. 357,421

3 Claims. (Cl. 102—79)

(Granted under the act of March 3, 1883, as amended April 30, 1928; 370 O. G. 757)

1

This invention relates to a fuze for use in projectiles that spin about their longitudinal axes and more particularly to a fuze that is armed by the centrifugal force of its rotation.

Among the several objects of this invention are:

To provide a fuze that is safe to handle when in the unarmed condition but is readily armed when a projectile provided therewith is in flight;

To provide a fuze that is simple in construction but effective in operation; and

To provide a fuze that does not require an air driven propeller to actuate the elements thereof to change it from unarmed to armed condition.

In the drawings:

Fig. 1 is an elevational view of a bomb provided with a fuze that embodies the present invention, with parts in section;

Fig. 2 is an axial section of the fuze substantially on the line 2—2, Fig. 3;

Fig. 3 is a transverse section of the fuze on the line 3—3, Fig. 2; and

Fig. 4 is a fragmentary longitudinal section similar to Fig. 2 but depicting the parts of the fuze in their armed positions.

While the present invention is illustrated and described in connection with a bomb of the spinning type, it is adapted for use in projectiles of any kind, such as those fired from a rifled barrel, that spin during flight.

The bomb 5 is provided with tail vanes 6 that are given an angular pitch to cause the bomb to rotate during flight as indicated by the dot and dash line 7. Ordinarily, if the vanes 6 have a pitch of 5° the fuze will be armed before impact but if more rapid arming is desired the pitch of the vanes 6 may be increased to as much as 10°, when a fall of approximately 100 ft. will suffice to effect the arming of the fuze.

Fuze 8 comprises two body members 9 and 10 that are held in assembled relation by the sheet metal member 11 spun over the conical nose of member 10 and over the shoulder of the member 9. In the cavity 12 formed in member 9 the detonator holder 13 is mounted to swing about pivot 14. The detonator holder 13 has a portion 15 that covers the booster lead 16 when the parts are in unarmed condition and a detonator 17 so positioned that when detonator holder 13 turns on pivot 14 the detonator 17 is brought into registration with booster lead 16. The path followed by detonator 17 when moving to the armed position is shown by broken line 18.

Spiral spring 19 has one end attached to pin 20 fixed in body member 9 and the other end

2

secured to pin 21 carried by detonator holder 13 and, as shown in Fig. 3, when the parts are in unarmed condition the spring 19 is bent into substantially U-shape. Spring pressed detents 22 and 23 engage recesses in the detonator holder 13 to lock the detonator holder in unarmed position but when the fuze spins the centrifugal force disengages detents 22 and 23 from detonator holder 13, thus permitting spring 20 to straighten out and rotate detonator holder 13 to the armed position. The position of spring 19 when the fuze is armed is indicated by dot and dash lines 19' and the armed position of pin 21 is shown at 21'.

15 Mounted in body member 10 for movement along the axis of the fuze is the firing pin 24 having an impact head 25 that extends beyond the nose of body member 10, and a collar 26 adjacent the inner end or point 27 thereof. In the unarmed condition spring pressed detents 28 and 29 engage the inner face of collar 26 to lock the firing pin and prevent inward movement thereof but when the fuze spins the detents 28 and 29 are withdrawn by the centrifugal force and the firing 25 pin is free to move inwardly. To prevent firing of detonator 17 by air pressure on impact head 25 before the bomb strikes an object, the separator disc 30 is interposed between the point 27 of firing pin 24 and the detonator 17. The disc 30 is sufficiently strong to withstand puncture due to air pressure on impact head 25 but is readily penetrated by firing pin 24 upon impact of head 25 against an object. The shank of firing pin 24 is sufficiently rigid to puncture disc 30 and fire detonator 17 when detents 28 and 29 have been moved out of engagement with collar 26, but if the fuze is inadvertently dropped while detents 28 and 29 are engaged with collar 26 the firing pin 24 will bend and absorb the movement of impact head 28 by deformation of the shank of the firing pin.

The invention herein described and claimed may be used and/or manufactured by or for the Government of the United States of America for governmental purposes without the payment of any royalties thereon or therefor.

I claim:

1. A fuze for projectiles that spin about their longitudinal axes, comprising a body, a booster charge therein, an axially extending booster lead connected to said charge, a detonator holder pivoted intermediate its ends and having a portion that covers said booster lead when said fuze is unarmed, a detonator in said holder positioned 50 to be brought into registration with said booster

lead when said holder is rotated into armed position, two spring pressed detents disposed substantially at right angles to each other and engaged with said holder to retain said holder in unarmed position but disengageable therefrom by centrifugal force, an elongated spiral spring having one end attached to said body and the other end attached to said holder to be bent into a substantially U-shape when said holder is in unarmed position and to straighten out to rotate said holder to armed position when said detents are released, a firing pin mounted to be slidable along the axis of said body and in alignment with said booster lead, said firing pin having a collar adjacent its inner end, spring pressed firing pin detents disposed diametrically opposite each other and engaged with the inner face of said collar to hold said firing pin in retracted position spaced away from the detonator holder, said diametrically disposed detents being releasable by centrifugal force, an impact head on the outer end of said firing pin, and a separator disc disposed between the inner end of said firing pin and said detonator holder, said separator disc being constructed to hold said firing pin against movement toward said detonator under force of air pressure on said firing pin when said firing pin detent means is out of engagement with said collar, but being constructed to be penetrated by said firing pin under impact, said firing pin being entirely spaced away from said detonator holder with said separator disc therebetween except upon penetration of said disc by said firing pin.

2. A fuze for projectiles that spin about their longitudinal axes, comprising a body, a booster charge therein, an axially extending booster lead connected to said charge, a detonator holder pivoted intermediate its ends and having a portion that covers said booster lead when said fuze is unarmed, a detonator in said holder positioned to be brought into registration with said booster lead when said holder is rotated into armed position, spring pressed detent means engaged with said holder to retain said holder in unarmed position but disengageable therefrom by centrifugal force, an elongated spiral spring having one end attached to said body and the other end attached to said holder to be bent into a substantially U-shape when said holder is in unarmed position and to straighten out to rotate said holder to armed position when said spring pressed detent means are released, a firing pin mounted in alignment with said booster lead to be slidable along the axis of said body, said firing pin having a collar adjacent its inner end, spring pressed firing pin detent means engaged with the inner face of said collar to hold said firing pin in retracted position spaced away from said detonator holder but releasable by centrifugal force.

3. A fuze for projectiles that spin about their longitudinal axes, comprising a body, a booster charge therein, an axially extending booster lead

connected to said charge, a detonator holder pivoted intermediate its ends and having a portion that covers said booster lead when said fuze is unarmed, a detonator in said holder positioned to be brought into registration with said booster lead when said holder is rotated into armed position, spring pressed detent means engaged with said holder to retain said holder in unarmed position but disengageable therefrom by centrifugal force, an elongated spiral spring having one end attached to said body and the other end attached to said holder to be bent into a substantially U-shape when said holder is in unarmed position and to straighten out to rotate said holder to armed position when said spring pressed detent means are released, a firing pin mounted in alignment with said booster lead to be slidable along the axis of said body, said firing pin having a collar adjacent its inner end, spring pressed firing pin detent means engaged with the inner face of said collar to hold said firing pin in retracted position spaced away from said detonator holder but releasable by centrifugal force, a separator disc interposed between the inner end of said firing pin and said detonator holder, said separator disc being constructed to hold said firing pin against movement toward said detonator under force of air pressure on said firing pin when said firing pin detent means is out of engagement with said firing pin collar but being constructed to be penetrated by said firing pin under impact, said firing pin being sufficiently rigid to puncture said disc upon impact on said firing pin when said firing pin detent means is out of engagement with said collar, and said firing pin being constructed to bend and absorb movement of its impact head by deformation of the shank of the firing pin under accidental impact when said firing pin detent means is engaged with the inner face of said collar.
